UNITED STATES PATENT OFFICE.

WINFIELD S. BANGS, OF ALMA, MICHIGAN.

SWINGING GATE.

SPECIFICATION forming part of Letters Patent No. 311,714, dated February 3, 1885.

Application filed February 7, 1884. (No model.)

To all whom it may concern:

Be it known that I, WINFIELD S. BANGS, of Alma, in the county of Gratiot and State of Michigan, have invented a new and useful Improvement in Swinging Gates; and I do hereby declare the following to be a full, clear, and exact description thereof, reference being had to the accompanying drawings, and to letters of reference marked thereon, in which—

10 Figure 1 is a perspective view of an improved gate with my improvements attached. Fig. 2 is a detail view of the T-shaped casting. Fig. 3 is a detail view of post B. Fig. 4 is a detail in perspective of the casting K and its connections.

15 My invention relates to that class of gates adapted to be opened or closed by persons either on foot, on horseback, or in vehicles; and it consists of the combination of devices hereinafter described and claimed.

To enable others skilled in the art to make and use my invention, I will proceed to describe the exact manner in which I have carried it out.

In the said drawings, A represents the post to which the gate is hung in the usual manner, and B is the front post, to which the gate latches.

On the post A are secured the cross-beam b and the braces b'. This cross beam has openings d formed near its outer ends, in which are pivoted the levers e, and to the long arm of each of these levers (which, if necessary, may hang over the center or side of the road) is attached a cord or wire, f, which is used as a hand-rope in opening and closing the gate.

On each side of the post A are the bell-crank levers C C, pivotally secured to the said post by a bolt or any well-known means.

To the arms c of the bell-crank levers are secured rods D, which pass upward and are attached to the short arms of the levers e, and to the arms c' of the levers are secured short chains or rods g, firmly secured to the outer ends of the T-shaped casting K, having flanges h, by which it is bolted or otherwise secured to the uprights E² of the gate F, which is composed of a series of horizontal rails, l, connected by the uprights E E² at each end and in the center, and has one or more diagonal braces and a cap-board, H.

To the chains or rods g, at a point near where the said rods are connected to the T-shaped casting, are secured chains 5 and 6, their opposite ends being connected to a draw-rod, H', secured in staples located on the top of the 55 cap-board H.

I is a latch pivoted within short uprights i, and having its free end adapted to engage a catch secured to the post B. This post B has a portion of its inner face, near the top, 60 cut away, as at m, and has inclines n n formed thereon, upon which the latch I rides as the gate is being closed or opened. From the upper part of the cut-away portion projects a depending stop, r, which will arrest the movement of the latch in either direction and cause the same to drop into a slot, s, sufficiently wide to allow the latch to be raised clear of the stop r when the gate is opened in either direction. The latch I is connected to the 70 draw-rod by a short chain passing over a pulley or stud, h', secured to the cap-board.

M represents a latching-post, one of which is placed on each side of the gate, adapted to engage and secure the gate when the same is 75 swung open in either direction.

The operation of my device is as follows: When it is desired to open the gate, the operator, either on foot, on horseback, or in a vehicle, has only to pull the hand-rope f, which 80 will cause the short arm of the lever e to draw on the rod D. This movement, by means of the bell-crank levers and draw-rods, will cause the latch to be lifted from the catch placed on the inside of the post B.

I do not mean to limit myself to this exact construction, for, if desirable, the bell-crank levers can be inverted and their short arms secured by rods to a lever, o, loosely pivoted to the post A near its base, as shown in 90 dotted lines in Fig. 1. The lever o projects some distance from the gate and has a bend, over which the wheels of an approaching vehicle are driven when it is desired to open or close the gate.

I am aware it is not new to secure upon the cap-board a plate having upturned ends; nor is it new to operate the latch by means of cords or ropes connected to or passing through said plate.

85

95

100

I am also aware it is not broadly new to secure a bell-crank lever on a post and connect it with a rope or chain for opening and closing a gate, and these features I do not claim, broadly, as my invention.

Having thus fully described my invention, what I claim as new, and desire to secure by Letters Patent, is—

In a swinging gate, the combination of the

pivoted levers *e*, rods *D*, bell-crank levers *C*, 10 secured on each side of the post *A*, the chains or rods *g*, T-shaped casting *K*, chains *5* and *6*, the draw-bar, and a latch, substantially as and for the purpose set forth.

WINFIELD S. BANGS.
